COLD WATER TUBE AND CLEANER FOR DOMESTIC BOILERS AND HEATERS

Filed Aug. 9, 1927

UNITED STATES PATENT OFFICE

WILLIAM EIERMANN, OF BROOKLYN, NEW YORK

COLD-WATER TUBE AND CLEANER FOR DOMESTIC BOILERS AND HEATERS

Application filed August 9, 1927. Serial No. 211,759.

This invention relates to domestic boilers and heater cleaners, and particularly to an improved cold water tube cleaner capable of being used temporarily or permanently, and 5 acting both as a cleaner and as a cold water supply tube.

The object of the invention is to provide an improved construction to be used with domestic boilers, heaters and the like, where- 10 in a clean-cut tube is provided which may be used by workmen for cleaning out a boiler or heater or may be used as a combined cleaner and a cold water supply pipe.

Another object of the invention is to pro- 15 vide a cleaner for boilers or heaters, wherein improved means are provided for readily applying and removing the cleaner.

A further object of the invention is to provide a flexible tube so that it may be 20 inserted into a boiler without taking the boiler down, and may be installed with or without a sprinkler head.

In the accompanying drawing—

Figure 1 is a vertical sectional view 25 through a domestic boiler of usual construction, with a cleaner embodying the invention shown applied thereto.

Figure 2 is an enlarged fragmentary vertical sectional view through the connections 30 of the cleaner and remaining parts of the device shown in Figure 1.

Figure 3 is an enlarged vertical sectional view through the lower end or distributing end of the cleaner shown in Figure 1.

Figure 4 is a bottom plan view of the structure shown in Figure 3.

Figure 5 is a modified form of cleaner end to that shown in Figure 2.

Figure 6 is a view similar to the lower 40 part of Figure 1, but showing the cleaner used in a different manner.

Figure 7 is a view similar to the lower part of Figure 1, but showing a special outlet.

Figure 8 is a side view with certain parts 45 broken away, illustrating the cleaner applied to what is commonly known as an instantaneous heater.

Referring to the accompanying drawing 50 by numerals, 1 indicates an ordinary do-

mestic boiler of usual construction having the usual inlets and outlets and other attachments. Ordinarily, a boiler of this kind is provided with a cold water pipe 2 as shown in Figure 6, the same being connected through the coupling 3 with the supply pipe 4. As indicated in Figure 1, pipe 2 has been removed and the cleaner or cleaner tube 5 substituted. This cleaner is formed of a flexible metallic tubing having at the upper end a sleeve 6 screwed thereon, 55 said sleeve having substantially the same conformation as the exterior of the tube 5. This sleeve has, however, a flange 7 either integral therewith or rigidly secured thereto. This flange rests on top of the flange 8 of the short tube or fitting 9 screwed into the member 10 forming part of the boiler 1. A coupling nut 11 acting on flange 8 and on the threaded portion 12 of the 60 sleeve 13, firmly clamps the various parts together as shown in Figure 2 so as to produce a water-tight connection. Sleeve 13 is screwed onto pipe 4 in the usual manner. When the parts have been connected up as 65 just described, water may be turned on by actuating a suitable valve interposed somewhere in pipe 4. As the water passes from pipe 4 through the cleaner 5, it will move downwardly and finally be discharged out the end 14 where it will be sprayed as indicated in dotted lines in Figure 1. This spray stirs up the mud and all foreign matter resting on the bottom 15 so that the 70 muddy water may be readily drawn off through the usual draw off cock 16. Before 75 water is turned onto the cleaner 5, all the water in the boiler 1 is drawn off through cock 16 so that as the water forms the spray 80 85 90 95 100 16, said spray will land directly on the mud and other foreign matter, whereby the same may be quickly loosened up so as to be a little later drawn off through cock 16.

The spray 17 is formed by a cone 18 which is fitted into a sleeve 19 having a flaring end 20. The cone 18 is provided with a cross-shaped body 21 soldered or otherwise rigidly secured to the sleeve 19 whereby when said sleeve is screwed into the lower end of the cleaner 5 and water is turned on, 100

said water will move out in a cone-shaped sheet through the opening or slit 22.

In many places, the top of the domestic boiler 1 is near the top of the kitchen or other room, and consequently, the regular spray tube 2 cannot be removed until the boiler has been completely taken down. For this reason, the cleaner tube 5 may be left permanently in place if desired, and also if desired, may be removed without taking the boiler down. Also, if preferred, the tube 2 may be removed or may be loosened and dropped down into the boiler and then the cleaner 5 inserted, even though the ceiling of the room is very near the top of the boiler 1. The cleaning action then may take place and if desired, tube 5 left in place as the cold water tube. Under some circumstances, the cleaner 5 is inserted through the fitting 23 as shown in Figure 6, and the cleaning action performed by turning on water as above described and later draining the same through the cock 16. The fitting 23 is the usual member for connecting a hot water coil to the boiler or for connecting the boiler to the fireback of a range.

It has also been found desirable to provide a drain off structure 24 at the edge of the bottom 15. This is provided usually when a new boiler is being made or set up. This permits all of the mud to be removed quickly and easily as this is at the lowest point of the boiler. When draining off through the structure shown in Figure 1, the bottom 15 near the periphery is not very well drained unless a rather large amount of water is used, so that wherever possible, the special drain off pipe 24 is preferable.

In the ordinary instantaneous heater as shown in Figure 8, difficulty has been experienced in cleaning the same. In the embodiment of the invention shown in Figure 8, the cleaner 5 is used in the usual way and is connected up as a substitute for the cold water pipe. However, a special drain off pipe 25 is provided at the lowermost point of the boiler so as to drain the periphery of the bottom 26 as well as the entire surface. A suitable valve 27 is connected with pipe 25 so that the boiler may be drained off at any time. The cleaner tube 5 may be used by workmen to clean a boiler, or may be used to take the place permanently of the usual cold water tube. When acting as a cold water tube, the boiler is continually full of water and, consequently, the spray 17 will ordinarily be a gentle inflow of water. This inflow of water usually is sufficient to maintain the bottom of the boiler clean, but in case sediment should accumulate, water may be turned off of the tube 5, boiler 1 drained, and then water turned on again through tube 5 for providing spray 17. This will effectively wash the bottom 15 and thus provide a clean boiler.

As indicated in Figure 1, means are provided which may be operated for swinging the tube 5 to distribute to a greater extent, the water over the bottom during the heating operation. This device consists of a packing gland 28, through which a rod 29 extends, said rod at the outer end carrying a handle or knob 30, whereby rod 29 may be rocked back and forth. This rod is bent or provided with a crank portion 31, merging into a fork 32 which continually straddles the pipe 5 so that it may sway this pipe back and forth. The packing gland 28 is sufficiently tight to prevent any leakage, and may be of any desired structure. If desired, gland 28 may be loosened when knob 30 is to be operated, and then again tightened after the cleaning operation has been performed. This device is intended primarily to be used by other persons than plumbers, whereby a housekeeper may readily and thoroughly clean the boiler. It is, of course, evident that plumbers may use this device if desired, and will always use the device wherever installed. This device is shown on an ordinary domestic boiler, but it could be used on water heaters as shown in Fig. 8, or other boilers, without departing from the spirit of the invention.

What I claim is:

1. A cleaner for domestic boilers and the like, comprising a flexible tube of metal formed as a thread, means at the upper end for operatively connecting the tube with the boiler and water supply, and means at the lower end presenting a spray structure, said spray structure including a sleeve formed as a thread adapted to be screwed into and out of the lower end of said tube, a stem cross-shaped in cross section fitting into said sleeve and a cone positioned at the end of said stem whereby water passing the stem will be divided into several streams and then into a conically shaped shower.

2. In combination, a domestic boiler formed with a cold water inlet, said inlet comprising an internally-threaded ring member permanently secured to the shell of the boiler at the top, a tubular fitting screwed into said ring, said fitting forming a flange, a sleeve having threads at each end for connecting a pipe to said tubular fitting and a coupling nut engaging the flange on said fitting and certain of the threads on said sleeve for clamping the sleeve to the fitting, and a flexible tube provided with a flange fitting between the flange on said tubular fitting and said sleeve, whereby it is clamped in position when said coupling nut is tightened, said flexible tube extending through said tubular fitting and to a point near the bottom of the boiler for discharging water near the bottom of the boiler.

3. The combination with a boiler having

10 a cold water inlet provided with means for
clamping a cold water distributing pipe in
the boiler, of a flexible tube extending into
the boiler having a spray nozzle at its inner
end and a flange at its outer end, said flange
5 being positioned to be secured in place by
said means for clamping a cold water distributing pipe in the boiler.

WILLIAM EIERMANN.
